UNITED STATES PATENT OFFICE.

ALFRED RALPH JOHNSON, OF GLOVERSVILLE, NEW YORK.

GAS-COCK.

1,181,315.

Specification of Letters Patent.

Patented May 2, 1916.

Application filed June 22, 1915. Serial No. 35,586.

To all whom it may concern:

Be it known that I, ALFRED RALPH JOHNSON, a citizen of the United States, residing at Gloversville, in the county of Fulton and State of New York, have invented a new and useful Gas-Cock, of which the following is a specification.

This invention relates to improvements in gas cocks, and the object is to provide a locking means for the same which will render impossible the accidental opening of the cock, after being shut off, thus preventing the escape of the non-ignited gas, the said means also acting as a lock for the turning 10 plug of the cock in open position to maintain a steady, full flow of gas to the burner, and to provide against the accidental cutting off of the gas supply when it is desired to leave the same in full flow. To accomplish these results a simple means is applied to the stem of the turning plug of any ordinary gas cock, said means being almost completely housed within a slot or recess provided in the stem, and having no projecting 15 parts to be accidentally caught by the sleeve or otherwise to cause the opening or closing of the cock, it being only necessary in order to move the plug from an open or a closed position, to press the upper end of the locking 20 means by the thumb while the fingers of the same hand grasp the usual turning handle of the gas cock.

A full and complete understanding of the invention may be obtained from a careful 35 consideration of the following detailed description, taken in conjunction with the accompanying drawing, forming a part of this specification; it being understood that while the drawing shows a practical form of 40 the invention, the latter is not confined to strict conformity therewith, but may be changed or modified, as long as such changes or modifications mark no material departure from the salient features of the invention, 45 as specifically pointed out in the claim hereto appended.

In the drawing, in which like reference characters designate corresponding parts in each of the several figures, Figure 1 is a 50 perspective view of a gas cock of the ordinary type, having my improved lock applied thereto. Fig. 2 is a vertical longitudinal sectional view of the same. Fig. 3 is a vertical sectional view taken at right angles to Fig. 2. Fig. 4 is a horizontal sectional view on the line 4—4, Fig. 2.

The usual vertically disposed tubular casing 1 has a tapered longitudinal bore 2 in which is seated the valve plug 3 of the ordinary construction, and adapted to be maintained on its seat, within the tapered bore, by the spring 4 bearing, at one end, against the washer 5 which closes the lower small end of the tapered bore 2, and bearing at its other end against the smaller washer 6 60 which is screwed or otherwise secured to the end of the reduced stem 7 formed at the lower end of the turning plug 3 and projecting beyond the lower face of the tubular casing 1 a distance sufficient to receive the 65 spring 4, all of which is common to cocks or valves of this type. In addition to this, the tubular casing is provided with the oppositely disposed integral nipples 8 and 9 arranged intermediate the top and bottom of the casing 1 and forming inlet and outlet openings respectively which, as is customary, may be connected with any suitable source of gas supply on the one side and any style of gas burner on the other, the usual horizontal 70 bore 10 being provided through the turning plug 3 in a position to register with the bores, provided in the nipples 8 and 9, in order to provide an uninterrupted passage-way through the same when the plug is 75 turned to an open position, or to be entirely cut off when the plug is given a one-quarter turn in the usual manner. The tubular casing is provided at its top edge with a cut-away portion 11 extending preferably, 80 though not necessarily, from a point directly over the longitudinal central line of the inlet nipple 8 around to one side a distance equal to ninety degrees, and provided at its terminals with seats or depressions 85 12 and 13 which are slightly deeper than the 90 arcuate cut-away portion 11.

The turning plug 3 is provided with the usual upstanding stem 14, and the laterally projecting handle 15 for turning the plug 100 from a closed to an open position, or vice versa, and said stem 15 has formed therein, at right angles to the axis of the laterally projecting handle 15, a slot 16, extending from top of the stem to a point considerably 105 below the top edge of the casing 2. The slot 16 is formed intermediate its ends with a counterbore 17, which is of a somewhat larger diameter than the width of said slot and extends from the outer face of the stem 110 14 to a point slightly beyond the bottom or inner wall of the slot. A locking lever 18

is adapted to fit the slot 16 and conforms approximately, on its outer edge, to the contour of the stem 14, and on its opposite or inner edge with the inner wall of the slot 5 and is formed of suitable metal of a thickness slightly less than the width of the slot. The lever 18 is provided at its lower end with an inwardly extending eye 19, through which passes a pin 20 which pivots the lever 10 within the stem 14, and said lever is further provided at its lower extremity with an outwardly extending lug or nose 21, which is adapted to enter one or the other of the depressed seats 12 and 13 during the operation 15 of opening or closing the valve. In order to insure the positive entering of the seats by the lug 21, a coiled spring 22 is introduced into the counterbore 17, said spring having one end bearing against the end wall 20 of the counterbore and the other end entering a recess 23 formed in the inner or rear edge of the lever 18 and acting to maintain, at all times, an outward pressure upon the lever and a consequent downward tendency 25 to the lug 21. By this construction it is impossible to dislodge the spring 22 from its proper position.

Assuming that the gas cock is in its closed position, as shown in Fig. 1 of the drawing, 30 it will be seen that in the natural manner of grasping the turning handle to open the cock to allow the flow of gas, the thumb will be in the exact position to press the lever 18 and thus raise the lug 21 from the depressed 35 seat 12 and permit of the turning of the plug until the said lug strikes the end wall of the cut away portion of the casing, when by releasing the handle the spring 22 forces the lug into the opposite seat 13 and the 40 device is locked in the open position. The same operation, as will be seen, takes place in the opposite movement of the handle. When the lever is forced outwardly by the 45 spring, it extends but slightly beyond the edges of the slot and thus there is little

chance of the said lever being accidentally caught by the sleeve of the operator or otherwise. The depth of the slot is sufficient to permit of the upper portion of the lever being pressed entirely thereinto by the thumb 50 of the operator.

While the device of the present invention has been shown and described as applied to a gas cock of an ordinary construction, it will be understood that the same is capable 55 of use in controlling the plugs of valves for other purposes.

What is claimed is:—

In combination with a casing, a turning plug, a stem provided on the plug in alignment therewith and projecting from the casing and having an operating handle, a slot formed longitudinally in the stem from the casing to the outer end thereof at right angles to the handle, a locking lever exteriorly conforming to the contour of the stem and extending within the slot and pivotally mounted at its inner end adjacent to the casing, a spring for exerting an outward pressure on the lever to cause it to project 70 partially from the slot, said spring being applied beyond the pivotal point, said lever having an outstanding lug adjacent its pivot, a cut-away portion provided on the adjacent end of the casing and extending around a 75 portion of the circumference thereof, said cut-away portion terminating at each end in locking seats, said seats being adapted to be entered by the outstanding lug on the lever to lock the same, together with the valve 80 plug, in open or closed position, said lug serving to limit the movement of the turning plug in either direction.

In testimony, that I claim the foregoing as my own, I have hereto affixed my signature in the presence of two witnesses.

ALFRED RALPH JOHNSON.
